CLAIM

The ornamental design for a multi-function bracket, substantially as shown and described.

DESCRIPTION

FIG. 1 is a bottom, front and right side perspective view of a multi-function bracket, showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a perspective view thereof, but showing the bracket expanded; and,

FIG. 9 is another perspective view thereof.
